UNITED STATES PATENT OFFICE.

FREDERICK T. CONLEY, OF BOSTON, MASSACHUSETTS.

PIPE EXPANDING, CUTTING, OR NURLING TOOL.

1,335,660.

Specification of Letters Patent. Patented Mar. 30, 1920.

Application filed March 8, 1919. Serial No. 281,325.

To all whom it may concern:

Be it known that I, FREDERICK T. CONLEY, a citizen of the United States, residing at Boston, in the county of Suffolk and 5 State of Massachusetts, have invented certain new and useful Improvements in Pipe Expanding, Cutting, or Nurling Tools, of which the following is a specification.

This invention has for its object the provision of a compactly arranged and inexpensive hand tool for use in cutting, milling or expanding the ends of pipes, being particularly designed for use by automobileists or others who may be called upon 15 to make repairs to marine, steam or gas engines having small pipes in their organization. The present device is related to and an improvement upon or addition to the device shown in a patent granted to me Feb. 20 18, 1919, No. 1,294,404.

In the accompanying drawings:

Figure 1 is a perspective view of a tool embodying my present improvements;

Fig. 2 is an end view of the tool with 25 a pipe in transverse section;

Fig. 3 is a detail sectional view of one of the gripping jaws;

Fig. 4 is a longitudinal section through the working parts of the tool;

Fig. 5 is a detail perspective view of the 30 turntable;

Fig. 6 is a perspective view of the pipe cutter and the spring by which the main body members are normally held separated.

Fig. 7 is a detail view of the reamer.

The tool comprising my invention consists primarily of two body members crossed near their working ends and pivotally connected at the point of crossing by a bolt 1.

The shorter portions of these body members constitute jaws 2 and 3 while the longer portions thereof constitute handle members 4 and 5, the extremity of one of 40 said handle members being forked, as

shown at 6, and provided with teeth or serrations 7 on one edge of the fork whereby it may be utilized as a wrench. The free ends of the handle members are connected by a screw or bolt 8 having a wing nut 9 45 mounted thereon and bearing against the outer face of one of the members, preferably the member 4 which is provided with the wrench or forked portion 6. The opposite end of the screw or bolt 8 is pivoted to

55 the extremity of the handle member 5, and

a conical serrated or corrugated body 10, which constitutes a reamer for increasing the diameter of an opening or the bore of a tube, is secured to said member 5 at the outer side thereof. The gripping jaw 2 60 carries a web 11 which may be secured thereon in any desired manner or formed integral therewith and in the said web is mounted two or more rollers 12 to engage against the side of the pipe upon which the 65 tool is to operate. The gripping jaw 3 is bifurcated and the edges of the members of said jaw are serrated, as shown at 13, so that they will obtain a firm grip upon the pipe placed between the jaws and hold it 70 against relative rotation as will be herein-after set forth. A spring 14 is coiled around the pivot bolt 1 and has its spaced divergent extremities 15 bearing against the inner faces of the handle members 4 and 75 5 so that the said members and the gripping jaws are normally held apart or in open relation. When it is desired to cause the jaws to grip a pipe or tube, the end of the tube or pipe is inserted between the 80 jaws and the nut 9 then rotated about the screw or bolt 8 so as to swing the ends of the handle members together which will obviously cause the jaws 2 and 3 to approach and bind against the pipe or tube so as to 85 firmly hold the same. Mounted to swing upon the pivot bolt 1 is a frame 16 having a handle member 17 and a bearing arm 18, a screw 19 being mounted in the said bearing arm, as shown. This screw is provided 90 with a conical head 20 which is adapted to enter the end of a tube or pipe held by and between the jaws 2 and 3, and as it enters the pipe, to expand the same as more fully set forth in my aforesaid application. 95

It will be readily observed, upon reference to Figs. 1 and 4 of the drawings, that the handle members 4 and 5 are grooved on their inner faces or substantially U-shaped in cross section and the upper portions of the jaws are bifurcated or slotted so that the members may cross each other and be pivotally mounted upon the bolt 1. Pivoted upon the bolt 1 and disposed between the members of the jaw 3 is the pipe 100 cutter 21 which is shown as a flat bar having its arms at opposite sides of its pivot point disposed at an angle to each other. The lower arm 22 is housed within the groove or hollow portion of the handle mem- 105 110

ber 4 and to the lower end of said arm 1 pivotally attach one end of an adjusting screw or threaded rod 23 which extends through an opening provided therefor in the handle member 5 and is equipped at the outer side of said member with a wing nut 24 and at the inner side of said member with a lock nut 25. It will be readily understood that by adjusting the said nuts 24 and 25 the bolt or threaded rod 23 will be caused to move through the handle member 5 and, consequently, will swing the arm 22 about the pivot bolt 1 so that the upper member or arm 26 will be caused to move toward or from the inner edge of the jaw 3 or the surface of a pipe held between the jaws. The upper arm 26 of the lever 21 is provided in one lateral face with a groove 27 in which is fitted a chisel-like cutter or blade 28, the said blade or cutter being secured within the groove by a set screw 29 so that it will effectually resist the thrust put upon it and will remain in proper position relative to the rod or tube being operated upon.

A circular frame 30 is mounted upon the pivot bolt 1 and is constructed with an annular inwardly projecting flange 31 at its inner side which fits against the inner face of the adjacent portion of the gripping jaw 3. The cylindrical wall of this circular frame is constructed with a slot 32 through which the said member of the jaw 3 is passed so that the frame will move with said jaw and will remain constantly in concentric relation thereto. Near the opposite end of the annular wall of this frame is a groove or recess 33 which receives a turntable 34 and a cap ring 35 whereby the turntable is held in position. The turntable consists of an annulus or flat ring provided with outstanding lugs 36 at diametrically opposite points and having a handle 37 secured to or formed integral with the ring between the said lugs, the said handle, as shown most clearly in Fig. 4, being shaped to extend through the cap ring 35 and then extend radially from the turntable and circular frame so that the required turning movement may be imparted to the table in the operation of the tool.

Flat sided screws 38 are inserted through the lugs 36 and to the inner ends of said screws are pivotally attached the ends of links 39, the inner opposed faces of all the links being serrated, as shown at 40, and the links attached to each bolt diverging from their pivotal connection therewith and having their ends remote from the bolts pivoted to the ends of the links extending from the opposed bolt, as shown at 41. A collapsible vise is thus provided which is adapted to fit around the pipe or tube, indicated at 42 in Fig. 2, and securely clamp the same against all relative turning movement. Winged nuts 43 are mounted upon the bolts 38 and bear against the outer faces of the

lugs 36 so that by rotating the said nuts, the bolts may be caused to move through the lugs and thereby expand or collapse the vise consisting of the pivotally connected links 39. A roller 44 may be provided upon the handle 37 to ride upon the external circumferential surface of the circular frame 30 and thereby aid in preventing lateral or rocking movement of the turntable in the frame.

It is thought the manner of using the tool will be readily understood. If it be desired to expand the end of a tube or pipe, the pipe is gripped between the jaws 2 and 3 and the frame 16 swung about the main pivot 80 or securing bolt 1 so as to bring the conical head 20 into axial alinement with the tube or pipe, after which the screw 19 is rotated in its bearing to cause the said head to enter the end of the pipe and thereby spread or 85 expand the same as previously stated. If it be desired to cut through a pipe so as to sever a section of any given length therefrom, the frame 16 is swung downward out of the way and the pipe is then inserted 90 through the links or jaws 39 and between the gripping jaws 2 and 3 until the required length of pipe or tube has passed beyond the cutter 28. The nuts 43 are then manipulated so as to cause the link jaws 39 95 to firmly clamp the pipe or tube, as shown in Fig. 2, after which the adjusting screw or bolt 23 is caused to move through the handle member 5 by manipulating the nuts 24 and 25 and the pipe cutter or lever 21 thereby 100 swung about the pivot bolt 1 so that the blade 28 will be caused to bear upon the pipe or tube, as shown in Fig. 2. The screw or bolt 8 then may be manipulated so as to bring the jaws 2 and 3 into engagement with 105 the pipe with just enough force to steady the movement of the tool and prevent bending or twisting of the pipe but should not be so manipulated that the jaws 2 and 3 will bind upon the pipe. The handle 37 is then 110 rotated about the axis of the frame 30 so that the turntable 34 with the link jaws 39 mounted thereon will be caused to move in a circular path within said frame, thereby causing the pipe or tube which is clamped 115 by and between said jaws to rotate about its own longitudinal axis. Inasmuch as the blade 28 is biting into the pipe, a groove will be cut in the surface of the same and the cutter will be adjusted after each complete revolution of the pipe so as to increase the depth of this cut and thereby gradually cut through the entire wall of the pipe so as to sever a section therefrom. After the pipe has been cut entirely through so that the desired section will be severed, the link members 39 are released from the main section of the tube or pipe and the gripping jaws 2 and 3 are also released so that the cut-off section may be removed and fitted where de- 120 125 130

sired. The tool may be also manipulated to nurl, mill, or roughen the surface of a tube or pipe which is to be inserted in an opening formed in or through a wooden member and when it is desired that the pipe or tube should obtain a firm gripping engagement with the wall of said opening. To accomplish this result, the tube or pipe is inserted through the vise composed of the link jaws 39 in the manner before described with the end of the pipe or tube disposed between the gripping jaws 2 and 3 and the cutter adjusted so that it will not come into contact with the pipe. The screw or bolt 8 is then adjusted so as to bring the jaws 2 and 3 into engagement with the pipe or tube so that the serrations 13 of the jaw 3 will bear firmly against the pipe but will not bind or grip into the same. If the turntable 20 be then rotated by means of the handle 37, the pipe will be caused to rotate between the jaws 2 and 3, moving easily upon the rollers 12, while the serrations 13 of the jaw 3 will scrape or wear upon the surface so as 25 to produce the desired roughening or milling.

From the foregoing description, taken in connection with the accompanying drawings, it will be seen that I have provided a very simple, compact and inexpensive tool which may be carried in an ordinary tool box and which may be efficiently employed for a variety of purposes. The tool is light and easily operated by an unskilled person so 35 that satisfactory repairs may be made in out of the way places and by persons who have no access to fully equipped machine shops or factories.

Having thus described the invention, 40 what is claimed as new is:

1. A tool comprising a pair of pivotally connected jaws, a frame carried by one of said jaws in fixed relation to the jaw by which it is carried, and a vise rotatably mounted in said frame and disposed to support work in a plane passing between said jaws.

2. A tool comprising a pair of pivotally connected jaws, a pipe cutter mounted upon the pivotal connection of said jaws and disposed within one of said jaws, and a rotatable work-holder mounted on the side of one of the jaws to support work between the working faces of the jaws.

3. A tool comprising a pair of pivotally connected jaws, one of said jaws having a serrated surface and the other of said jaws being provided with a movable work-support co-acting with said serrated surface, and a rotatable work-holder mounted on the side of one of said jaws and disposed to hold work in a plane passing between the jaws.

4. A tool comprising a pair of pivotally connected body members, a cutter housed 65 within one of said members and mounted

for movement relative thereto transversely thereof, and a rotatable work-holder mounted on the side of one of said members to support work in a plane passing between the members in operative relation to said cutter.

5. A tool comprising a pair of pivotally connected body members each having a jaw at one end, an adjustable connection between the opposite ends of said members whereby the jaws may be moved toward or from each other, work-performing instrumentalities supported by the body members adjacent the jaws and a rotatable work-holder mounted on the side of one of said jaws 70 whereby to support work between the jaws.

6. A tool comprising a pair of pivotally connected members, a lever pivoted between its ends upon the pivotal connection between said members and housed within one of said members, a blade carried by the upper end 85 of said lever, and an adjustable connection between the lower end of said lever and the opposite one of said members.

7. A tool comprising a pair of pivotally connected members, a lever pivoted between its ends upon the pivotal connection between said members and housed within one of said members, a blade carried by the upper end 95 of said lever, and adjustable connection between the lower end of said lever and the opposite one of said members, and a rotatable work-holder carried by one of said members.

8. A tool comprising pivotally connected 100 members having opposed jaws and provided with work-performing instrumentalities, a circular frame mounted upon the jaw of one of said members and projecting inwardly beyond the working face of the same, and a work-holder rotatably mounted in said frame and disposed in advance of said jaw.

9. A tool comprising a pair of pivotally connected members having opposed jaws and provided with work-performing instrumentalities, a circular frame mounted upon the side of one of said members, a turntable fitted for rotation in said circular frame, and a work-holder carried by said turntable whereby to support work between 115 the jaws of the pivotally connected members.

10. A tool comprising a pair of pivotally connected members provided with work-performing instrumentalities, a circular frame mounted upon one of said members, a turntable rotatably fitted in said frame, holding members mounted radially upon the turntable at diametrically opposite points, and work-engaging jaws pivotally connected to each other and to the inner ends of said 120 members.

11. A tool comprising a pair of pivotally connected members provided with work-engaging instrumentalities, a circular frame carried by one of said members, a turntable 130

rotatably fitted in said frame, lugs on the outer side of said turntable at diametrically opposite points thereof, adjusting members fitted in said lugs radially to the turntable, and work-holding jaws pivoted to the inner ends of the said adjustable members and having their meeting ends pivotally connected.

12. A tool comprising a pair of pivotally connected members having opposed jaws, an annulus fitted upon the pivot of said members and provided with a slot to receive one of the jaws whereby it will be maintained in fixed relation to said jaw, and a work holder

rotatably fitted in said annulus adjacent said jaw.

13. A tool comprising a pair of pivotally connected members having opposed jaws, an annulus secured to one of said jaws to move therewith about the pivot of the members, said annulus having an internal annular recess, a turntable fitted in said recess, a vise carried by said turntable, and means for retaining the turntable in the recess.

In testimony whereof I affix my signature.

FREDERICK T. CONLEY. [L. S.]
